CLAIM

The ornamental design for a real time data logger as shown and described.

DESCRIPTION

The patent or application file contains at least one drawing executed in color. Copies of this patent or patent application publication with color drawing(s) will be provided by the Office upon request and payment of the necessary fee.

1. Real time data logger
- 1.1 : Front
- 1.2 : Back
- 1.3 : Left
- 1.4 : Right
- 1.5 : Top
- 1.6 : Bottom
- 1.7 : Perspective
- 1.8 : Perspective

FIG. 1.1 is a front view of a real time data logger embodying our new design; FIG. 1.2 is a back view thereof; FIG. 1.3 is a left view thereof; FIG. 1.4 is a right view thereof; FIG. 1.5 is a top view thereof; FIG. 1.6 is a bottom view thereof; FIG. 1.7 is a perspective view 1 thereof; FIG. 1.8 is a perspective view 2 thereof.
